UNITED STATES PATENT OFFICE.

BERNARD D. WILLIS, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

ROTARY LINE SWITCH.

Application filed May 9, 1925. Serial No. 28,995.

This invention relates in general to automatic switches, but is concerned more particularly with switches of the automatic hunting type, commonly known as line switches. Switches of this character are used in automatic telephone systems, individual to each subscriber's line, and when used in this situation the function of each line switch is to select a trunk to an idle 10 succeeding switch, for example, a first selector, and connect the subscriber's line thereto.

The object of this invention is to provide new line switches of the rotary type 15 having a home or normal position in which the switch wipers normally rest. When a call is initiated, the wipers are rotated in a forward direction in search of a trunk to an idle succeeding switch, and come to rest 20 when they engage the contacts at which the conductors of a trunk to an idle succeeding switch terminate. When the call is over 25 with and the switches associated with the talking connection are released, the wipers of the line switch are again automatically rotated in the forward direction until they reach the home position.

The utility and advantages of the home-position type rotary line switch are commonly known to those familiar in the art, 30 so no discussion of these subjects is given.

The new line switches which form the subject-matter of this invention are illustrated by means of the usual schematic circuit diagrams in Figs. 1 and 2 of the accompanying drawing. Referring to this drawing, in Fig. 1 is shown a subscriber's telephone substation A with a line terminating at a central automatic exchange in the individual line switch LS, which is of the home-position rotary type. At the banks of the line switch access is had to first selector switches. These selector switches may be of any well known type, the vertical and rotary, for example, and are responsive to the first digit dialled by the calling subscriber. One of these selector switches is indicated in Fig. 1 by reference letter S, only those elements having to do with the 45 operation of the line switch being shown. A call from the substation A to another subscriber may be extended through line switch LS, selector S, and through other selectors, depending on the size of the system, and

through a connector switch to a called subscriber. 55

In Fig. 2 is shown a similar system; the subscriber's substation A', the line switch LS' and the selector S', only those elements of the latter having to do with the operation of the line switch being shown. Line switch LS' is similar in operation to line switch LS, except that line switch LS is arranged to operate with a common interrupter I, while in the line switch LS', the stepping magnet has its individual interrupter springs, and the circuits are adapted accordingly. 60

Having given a general explanation of the invention and the apparatus involved, the operation of the equipment will now be explained more in detail. For this purpose it will be assumed that the subscriber at substation A desires connection with some other subscriber in the exchange. To initiate the 70 call, the subscriber at substation A removes his receiver. Removing the receiver at substation A places a direct current bridge across the line conductors 2 and 3, thereby closing a circuit for the line relay 5 of the 75 line switch LS. This circuit may be traced from the grounded resting contact and armature 10, line conductor 3, through the substation A, line conductor 2, armature 7 and the resting contact, through the winding of 80 line relay 5 to battery. The wipers 23, 24, 85 25 are normally resting on the home-position contacts 20, 21, 22, respectively. Upon the energization of line relay 5, at armature 11 and the working contact ground is placed on 90 the private normal conductor 16 connected to the private contact in the connector banks to protect this line from being connected with by some other calling line. A circuit is also completed from ground by way of 95 armature 11 and the working contact, home-position contact 21, wiper 24, working contact and armature 12, through the lower winding of the switching relay 4 to battery. The upper winding of switching relay 4 is 100 short-circuited at this time by ground on both ends of this winding. Switching relay 4 is a marginal relay and adjusted so that when current flows through its lower winding only, the relay is energized just sufficiently to operate armature 9 to make contact with spring 18 without separating springs 105 17 and 18. The springs of line relay 5 are

adjusted so that armature 12 and its working contact close before armature 11 and its working contact close. This is to assure the proper partial operation of switching relay 4 at this time. A circuit is now completed for the stepping magnet 6 from ground by way of armature 11 and the working contact, armature 9, contact springs 18 and 17, through the winding of the stepping magnet 6, to the interrupter I which supplies interrupted battery. The interrupter I, as indicated by the small arrows to either side of the conductor connecting the interrupter to the magnet 6, is common to a plurality of line switches such as LS. As long as this circuit is maintained complete, the stepping magnet will energize and deenergize in response to interrupted battery from interrupter I. The stepping magnet is arranged to rotate the switch wipers on its return stroke, i. e., when it deenergizes. Upon the first deenergization of stepping magnet 6, the wipers 23, 24, 25 are rotated off the home-position to the next set of bank contacts. Cam 14 also rotates and closes springs 13 thereby preparing the return stepping circuit to be described later. If the first selector accessible at this set of contacts is busy, there will be ground on the private contact engaged by the private wiper 24 and the ground will be maintained on the junction of the upper and lower winding of the stepping relay 4. The circuit for the stepping magnet 6 is still maintained and on the next deenergization of the magnet 6 the wipers will be rotated to the next set of bank contacts. This stepping action will continue until the wipers 23, 24, 25, engage a set of contacts leading to an idle selector switch, the idle condition being indicated by no ground present on the private contact. It will be assumed that selector S, accessible at the line switch bank contacts 26, 27, 28, is the first idle selector found. Under this condition there is no ground on bank contact 27 and the upper winding of switching relay 4 is no longer short circuited and the relay will energize completely. In operating fully, armature 9 completes its stroke, separates springs 18 and 17 and makes contact with both springs 18 and 19. The circuit of the stepping magnet is thus opened and as a result the wipers 23, 24, 25 remain engaged with the bank contacts leading to selector S. The complete energization of switching relay 4 also results in the opening of a point in the return-stepping circuit, to be described later, at armature 8, and in the operation of armatures 7 and 10 which disconnects the line conductors 2 and 3 from the line relay 5 and ground, and connects them by way of wipers 23 and 25, bank contacts 26 and 28, armatures 33 and 35 and the resting contacts, through the upper and lower windings of the line relay 31

of the selector S to battery and ground, respectively.

The line relay 31 of the selector S energizes over the above traced circuit and closes a circuit for the release relay 32 at armature 36. Release relay 32 operates and places ground on conductor 38 at armature 37 thereby supplying a holding ground for the switching relay 4 of the line switch LS and a protecting ground to conductor 16, by way of bank contact 27 and wiper 24, before line relay 5 has had time to fall back.

The subscriber at substation A now dials the directory number of the substation with which connection is desired. In response to the first digit dialled, the selector S raises its wipers to the proper level of bank contacts, corresponding to the digit dialled, and then rotates its wipers in search of an idle trunk to a succeeding selector. In response to other digits dialled by the calling subscriber, other selectors operate in the well known manner, the number of selectors being determined by the size of the system. The operation of the succeeding switches is well known in the art and consequently need not be described. Responsive to the last two digits dialled, a connector raises its wipers and then rotates them to connect to the called line, automatically signals the called subscriber and finally completes the talking connection when the called subscriber answers. The subscribers may then hold conversation.

At the termination of the conversation the subscribers will replace their receivers on their respective switch-hooks. Replacing the receiver at substation A opens the direct current bridge across the line conductors 2 and 3. As a result, the selectors are released, in the well known manner, and the holding ground is removed from conductor 38. The switching relay 4 is deenergized and its armature springs are restored to normal. A return-stepping circuit is now completed for the stepping magnet 6 from ground by way of armature 11 and the resting contact, closed springs 13, the resting contact and armature 8, closed springs 18 and 17, through the winding of the stepping magnet 6, to the interrupter I which supplies interrupted battery. The stepping magnet 6 will now operate to rotate the wipers 23, 24, 25 step-by-step in the forward direction until they reach the home-position. At this position the cam 14 will again open the springs 13 thereby opening the return stepping circuit of the stepping magnet 6. Consequently, the wipers will remain resting in the home-position. The replacement of the receiver at the called substation effects the release of the connector as is well known and need not be discussed.

A brief explanation of the operation of line switch LS' may now be given and for

this purpose it will be assumed that the subscriber at substation A' desires connection with some other subscriber in the system. To initiate the call, the subscriber at substation 5 A' removes his receiver and dials the directory number of the substation with which connection is desired. Removing the receiver at substation A' places a bridge across the line conductors 2' and 3' and closes a circuit 10 for the line relay 5' of the line switch LS'. Line relay 5' energizes and places ground on the home-position private contact 21', on the lower end of the winding of the switching relay 4, and on the private conductor 16', at 15 armature 11'; and at armature 12' closes a circuit for the stepping magnet 6'. This circuit may be traced from ground on contact 21', wiper 24', armature 9' and the resting contact, the working contact and armature 20 12', interrupter springs 15', through the winding of the stepping magnet 6' to battery. Switching relay 4' is short-circuited at this time by ground on both ends of its winding. Stepping magnet 6' energizes and, 25 near the end of its stroke, opens its own circuit at the interrupter springs 15'. Stepping magnet 6' then releases and in so doing rotates the switch wipers 23', 24', 25', off the home-position to the next set of bank contacts. Cam 14' also rotates and closes 30 springs 13', thereby preparing the return-stepping circuit to be described later. If the selector accessible at this set of bank contacts is busy, the private contact engaged by the 35 private wiper 24' will be grounded and the circuit for the stepping relay 6' will again be completed and the wipers will be rotated to the next set of bank contacts. This stepping action will continue until the wipers 40 23', 24', 25' engage a set of contacts connected to an idle selector. It will be assumed that selector S', accessible at bank contacts 26', 27', 28', is the first idle selector encountered. Under this condition there will be no 45 ground on contact 27', engaged by wiper 24'. Relay 4', being no longer short circuited by ground on both ends of its winding, will be energized from ground by way of armature 11' and the working contact, through 50 the winding of switching relay 4', closed interrupter springs 15', through the winding of the stepping magnet 6' to battery. The stepping magnet does not energize at this time on account of the high resistance of relay 4'. Upon energizing, relay 4' prepares 55 a holding circuit for itself at armature 9', opens a point in the return stepping circuit to be described later at armature 8', and at armatures 7' and 10' disconnects the line 60 conductors 2' and 3' from ground and line relay 5' and connects them to the selector S' as similarly described in connection with the description of line switch LS'.

The succeeding operations are also similar 65 to those already described in connection with

the description of LS, and the talking connection is established in like manner.

When the subscribers replace their receivers at the termination of the conversation, the selector switches are released and the holding ground removed from conductor 70 38'. Switching relay 4' deenergizes and closes the return-stepping circuit at armature 8'. This circuit may be traced from ground by way of armature 11' and the resting contact, closed springs 13', armature 8' and the resting contact, closed interrupter springs 15', through the winding of the stepping magnet 6' to battery. The wipers are rotated in a forward direction to the home-position. At this position the return-stepping circuit is opened at springs 13' by cam 14', thereby preventing further movement 75 of the wipers.

Having described the invention, what is thought new and is desired to have protected by Letters Patent is set forth in the appended claims.

What is claimed is:

1. In a selector switch, a marginal relay, means for partially operating said relay to start the switch, and means for completely operating said relay to stop the switch. 90
2. In a trunk selecting switch, a two-step relay, a motor magnet, a circuit for said magnet closed by said relay in its first step and opened in its second, means for operating said relay in its first step to start the switch hunting, and means including a test circuit for preventing the relay from operating in its second step until an idle trunk is found. 95
3. In a trunk selecting switch, a relay operable in two stages, a motor magnet having a circuit closed by said relay in its first 105 stage of operation, two windings for said relay, means for energizing one winding alone to operate the relay in its first stage, whereby the operation of said magnet is initiated, and testing means for energizing the second winding also when an idle trunk 110 is found, whereby the operation of the magnet is stopped.
4. In a rotary line switch, trunk line contacts, a home position contact, a test wiper, means including a circuit extending through said wiper and said home contact for enabling the switch to start hunting, means including a circuit through said wiper and busy trunk contacts for continuing the hunting operation until an idle contact is found, off normal contacts, and a circuit including said off normal contacts for causing the switch to resume its movement and continue same until said wiper reaches said 120 home contact again.
5. In a telephone system, a plurality of line switches, each terminating in a subscriber's line, trunk lines accessible to said line switches in the banks thereof, means for 130

- indicating a busy or idle condition of said trunk lines, an interrupted battery supply common to said line switches, means in each line switch operable from said interrupted 5 battery supply for causing said line switch to connect to an idle one of said trunk lines in response to a subscriber initiating a call, and means in each line switch including said second named means for causing it to restore to normal position at the termination 10 of a call, said last named means also including normally closed switch contacts which are opened responsive to the selection of an idle trunk.
- 15 6. In a telephone system wherein electro-responsive means is provided for operating a trunk selecting switch, a two step marginal relay contacts of which are connected in a first operated position to establish a circuit to said means and in its second operated position to break the said circuit.
7. In a telephone system wherein electro-responsive means is provided for operating a trunk selecting switch, a two step marginal 20 relay connected in a first operated position to establish a circuit to said means, in its second operated position to break the said circuit, and in its normal inoperative position to establish a circuit for said means provided the switch is in any position other than one certain position.
8. In a telephone system wherein electro-responsive means is provided for operating a trunk selecting switch, a two step marginal 25 relay contacts of which are connected in a first operated position to establish a circuit to said means and in its second operated position to break the said circuit, and means for preventing the operation of said relay 30 into its second operated position until an idle trunk is reached.
9. In combination, a motor magnet, a switch controlling the circuit of said motor magnet, means for partially operating said 35 switch to close a circuit to said motor magnet, means moved under the control of said magnet to cause the complete operation of the switch to break the circuit to said motor magnet.
- 50 10. In combination, a motor magnet, a switch controlling the circuit of said motor magnet, means for partially operating said switch to close a circuit to said motor magnet, means moved under the control of said magnet causing the complete operation of the switch, means operated when the switch is completely operated to break the circuit to said motor magnet, and means effective upon the subsequent release of said switch 55 to cause the second named means to return to its initial position.
11. In a telephone system, a trunk selecting switch including a motor magnet and a relay controlling the circuit of said motor magnet, means for partially energizing said 60 relay to close a circuit for said motor magnet, a trunk selecting wiper moved under the control of said magnet, said wiper causing the complete energization of the relay, and means operated when the relay is completely energized to break the circuit to said magnet. 70
12. In a telephone system, a trunk selecting switch including a motor magnet and a relay controlling the circuit of said motor magnet, means for partially energizing said relay to close a circuit for said motor magnet, a trunk selecting wiper moved under the control of said magnet, said wiper causing the complete energization of the relay, 75 means operated when the relay is completely energized to break the circuit to said magnet, and means effective upon the deenergization of said relay to cause the wiper to return to its initial position. 80
13. In a telephone system a line switch including a trunk selecting wiper having a home position, a line relay, a switching relay, a magnet for moving the wiper, off normal contacts open when the switch is in the home position and closed when the switch is in any other position, and an operating circuit for said magnet extending when the switch is away from the home position through two branches, one of said branches being controlled through said wiper and including a front contact on the line relay and back contact on the switching relay, the other branch including back contacts on each of the two relays and the off normal contacts. 90
14. In a lineswitch of the homing type, a line relay, a switching relay, a motor magnet, a trunk hunting circuit for the magnet effective when the switch is away from the home position, said circuit including a back contact of the switching relay and a front contact of the line relay, and a homing circuit for the magnet including said back contact of the switching relay, and a second 100 back contact of the switching relay in series. 110
15. In a lineswitch of the homing type, a line relay, a switching relay, a motor magnet, a trunk hunting circuit for the magnet effective when the switch is in an off-normal 115 position, said circuit including a back contact of the switching relay and a front contact of the line relay in series, and a homing circuit for the magnet including a back contact on the switching relay and a back contact on the line relay in series. 120
16. In a lineswitch of the homing type, a line relay, a switching relay, a trunk hunting wiper having a home position contact, a circuit for the magnet for initiating the trunk hunting movement of the switch, said circuit being controlled over said wiper and the home contact and including a back contact on the switching relay and a front contact on the line relay in series, off-normal 125 139

contacts, and a homing circuit for the magnet controlled over said off-normal contacts.

17. In a lineswitch of the homing type, a line relay, a switching relay, a trunk hunting wiper having a home position contact, a circuit for the magnet for initiating the trunk hunting movement of the switch, said circuit being controlled over said wiper and the home contact of the switch and including a back contact on the switching relay and a front contact on the line relay in series, off-normal contacts, and a homing cir-

cuit for the magnet including said off-normal contacts, said back contact of said switching relay and a front contact of the line relay.

18. In a rotary line switch, a cut off relay, and a circuit for said relay extending through two sets of contacts on said relay in series.

In witness whereof, I hereunto subscribe my name this 6th day of May, A. D., 1925.

BERNARD D. WILLIS.
